Plamme & Birn.
Attorney

UNITED STATES PATENT OFFICE.

ULYSSES S. MEALEY, OF FARIBAULT, MINNESOTA.

HAND TRUCK.

Application filed May 28, 1925. Serial No. 33,421.

To all whom it may concern:

Be it known that I, ULYSSES S. MEALEY, a citizen of the United States, residing at Faribault, in the county of Rice and State 5 of Minnesota, have invented certain new and useful Improvements in Hand Trucks, of which the following is a specification.

The present invention relates to a hand truck, and has for its principal object to 10 provide a structure whereby articles such as boxes or the like may be easily engaged under by the hand truck, so that the articles may be easily and quickly lifted thereon.

Another important object of the invention 15 is to provide a hand truck of the above indicated character, which is simple in its construction, strong, durable, easy to manipulate, efficient, reliable, and otherwise well adapted for the purpose for which it is 20 designed.

With the above and numerous other objects in view, as will appear as the description proceeds, the invention resides in certain novel features of construction, and 25 in the combination and arrangement of parts, as will be hereinafter more fully described and claimed.

In the drawing:

Figure 1 is a top plan view of the hand 30 truck embodying the features of my invention.

Figure 2 is a similar view thereof, showing the parts in a different position, and

Figure 3 is an enlarged transverse section taken on the line 3—3 of Figure 1, looking in the direction of the arrow.

Referring to the drawing in detail, it will be seen that the numerals 5 designate a pair of handle bars, which are pivoted to the cross members 6, intermediate their ends. Straps 7 are fixed to the ends of the bars 5, for receiving pivot pins 8 in the ends of arms 9, which are pivoted between plates 10, and terminate in laterally extending hook shaped members 11. An axle 12 is associated with wheels 13 in the usual manner and are supported by brackets 14 depending from the lower plate 10. A guide rod 15 includes a pair of telescopically associated sections fixed, one to the plate 10, and the other to the cross member 6. A bowed leaf spring 16 is fixed intermediate

its ends to the cross member 6 and engages the bars 5 adjacent their ends, which are pivoted to the arms 9, and tend to normally hold the bars 5 in parallel relation as shown in Figure 1. By swinging the handle bars 5 away from each other, as is indicated in Figure 2, it will be seen that the extensions 11 may be moved away from each other, so that the truck may be moved adjacent an article and placed in a vertical position, and then by moving the handles toward each other, the extensions 11 will be forced under the article, and thus the truck may lift the article from the ground in the usual manner, and move to convey the article to the desired place. It is thought that the construction, operation, utility and advantages of the invention will now be clearly understood by those familiar with the use of an ordinary hand truck, without a more detailed description.

It is apparent that changes in the details of construction, and in the combination and arrangement of parts may be resorted to, without departing from the spirit or scope of the invention as hereinafter claimed or sacrificing any of its advantages.

Having thus described my invention, 80 what I claim as new is:

1. A hand truck of the class described including a wheel supported plate, a pair of arms pivoted to the plate and having extensions for engaging an article on one end, a cross member, a pair of handle bars pivoted to the cross member and having their ends pivotally engaged with the other ends of the arms, a spring between the handles for normally holding them in a parallel position.

2. A hand truck of the class described including a wheel supported plate, a pair of arms pivoted to the plate and having extensions for engaging an article on one end, a cross member, a pair of handle bars pivoted to the cross member and having their ends pivotally engaged with the other ends of the arms, a guide rod including a pair of telescopically associated sections, one fixed to the cross member and the other fixed to the plate.

3. A hand truck of the class described including a wheel supported plate, a pair

of arms pivoted to the plate and having extensions for engaging an article on one end, a cross member, a pair of handle bars pivoted to the cross member and having their ends pivotally engaged with the other ends of the arms, a spring between the handles for normally holding them in par-

allel position, and a guide rod including a pair of telescopically associated sections, one fixed to the cross member and the other fixed to the plate.

In testimony whereof I affix my signature.

ULYSSES S. MEALEY.
